UNITED STATES PATENT OFFICE.

JAMES F. M. FARQUHAR, OF BOSTON, MASSACHUSETTS.

SASH-BAR CONSTRUCTION FOR SKYLIGHTS IN GREENHOUSES.

939,592.

Specification of Letters Patent. Patented Nov. 9, 1909.

Application filed February 14, 1907. Serial No. 357,238.

To all whom it may concern:

Be it known that I, JAMES F. M. FARQUHAR, a citizen of the United States, and a resident of Boston, in the county of Suffolk and State of Massachusetts, have invented an Improvement in Sash-Bar Construction for Skylights in Greenhouses, of which the following description, in connection with the accompanying drawing, is a specification, like characters on the drawing representing like parts.

This invention has for its object to provide a novel sash-bar construction which is comparatively cheap to manufacture, and which will hold the glass of a glass-roof without any liability of its breaking due to unequal expansion of the parts.

In the drawings I have illustrated one embodiment of my invention; and Figure 1 is a sectional view in perspective through a sash-bar embodying my invention; Fig. 2 is a section on the line *x—x*. Fig. 1; Fig. 3 shows a different form of the invention.

The sash-bar comprises a body member 3, which is preferably of iron, on which the glass panes 4, 5, rest, and the parting member 6, which is preferably of wood, and which rests on and is secured to the body member as shown in the drawings.

The body member 3 is made with the head 7 having a substantially flat surface on which the parting member 6 rests, with the web 8 and with the two flanges 9 at its lower edge which form with the web gutters which carry off condensation water that collects therein.

In the embodiment of the invention shown in Fig. 1, the parting strip 6 is shown as having associated therewith two flanges 10 on which the glass 4 rests, a tight joint between the glass and flanges being made by putty 11 in the usual manner. The flanges 10 may either be integral with the parting strip 6, or separate therefrom, and they may be made of wood or even of felt 12 or some similar material. In Fig. 3 I have shown the latter construction wherein the strip of felt 12 is placed on top of the head 7 and between said head and the parting strip 6, the edges of said strip forming the rest for the glass 4, 5. The glass is shown as held in place by a suitable clip 14 which em-

braces the parting strip and is provided with two feet 15, 16 both of which are preferably resilient. I prefer to use one of these clamps at the point where the adjacent sections of glass overlap each other, and the foot 15 is made a little longer than the foot 16, so that the former foot 15 may rest on the lower pane of glass 4 while the foot 16 rests on the upper pane of glass. In this way the feet 15 form stops against which the lower edges of the upper panes 5 rest thereby to hold them in place. Both the feet 15, 16, are made resilient to permit the glass to yield slightly without any danger of breaking, if moisture which gathers under the panes should become frozen. With this construction the feet 16 serve to hold the upper panes in place while the feet 15 serve not only to hold the lower panes in place but they also act as stops for the upper panes.

Each clip 14 may be secured to the parting strip in any suitable way, and I have herein shown for this purpose a bolt 20 which may extend through the clip and parting strip into the body member 3, and thus serve both to hold the clip to the parting strip and the latter to the body member.

Having described my invention what I claim as new and desire to secure by Letters Patent is:—

In a sash bar construction, the combination with a metal body member presenting a web having at its upper edge a head provided with a flat top surface and having at its lower edge laterally-extending flanges which form gutters, of a wooden parting member resting on the flat top surface of said head and having at its lower edge laterally-extending, glass-receiving flanges, the under face of said flanges occupying the same plane as the under face of the parting member, and a clip embracing the parting member and provided with feet to rest on the glass.

In testimony whereof, I have signed my name to this specification, in the presence of two subscribing witnesses.

JAMES F. M. FARQUHAR.
